UNITED STATES PATENT OFFICE.

ABNER A. GRIFFING, OF JERSEY CITY, NEW JERSEY.

STEAM-RADIATOR.

SPECIFICATION forming part of Letters Patent No. 273,066, dated February 27, 1883.

Application filed December 9, 1882. (No model.)

To all whom it may concern:

Be it known that I, ABNER A. GRIFFING, of Jersey City, in the county of Hudson and State of New Jersey, have invented a new and useful Improvement in Steam-Radiators, of which the following is a full, clear, and exact description.

The object of the invention is to so construct a radiator-tube and its interior air-pipe that a maximum of heat will be applied to the air as it circulates through the interior pipes.

Reference is to be had to the accompanying drawings, forming a part of this specification, in which similar letters of reference indicate corresponding parts in all the figures.

Figure 1 is a side elevation, partly sectional, of a radiator with my improvements. Fig. 2 is a longitudinal section of one of the tubes in larger size. Fig. 3 is a longitudinal section at right angles to Fig. 2. Fig. 4 is a transverse section on line *x x*; and Fig. 5 a transverse section on line *y y*, Fig. 3.

A are the steam-tubes. B is the base, and C the cap, of the radiator. The tubes A are of flattened or oval form throughout their whole length, except at their upper ends, which are swelled to a circular form. At their lower ends they are formed with threaded flanges or bosses *a*, that are screwed into the upper plate 25 of the base B. Through the center of the steam-tubes air-tubes *d* pass, these air-tubes being screwed into the bottom plate of the base B and into the upper ends of the steam-tubes A, so as to form internal passages for

air from the under side of the base B to the cap 35 C. The external diameter of the air-tubes *d* corresponds to the internal shorter diameter of the steam-tubes, so that there is contact between the exterior surface of the air-tubes and the interior surface of the steam-tubes, and the 40 steam-tubes are thereby divided into two longitudinal passages for circulation of the steam, the two passages being connected at the upper end by the enlargement of the steam-tubes at that point. By this construction and arrangement 45 I obtain a largely-increased heating-surface in proportion to the size of the steam-tubes and insure a greater upward circulation of air. I do not limit myself to this special construction and arrangement, as they may be varied 50 within the scope of my invention.

I am aware that air-circulating pipes have been formed in steam or hot-water heating tubes by running two parallel partitions across the inside of a tube laterally open above the 55 bottom for the reception of air and closely covered at the top, below the top of the tube.

What I claim as new and of my invention is—

The combination of a flattened or oval tube, 60 A, swelled out in a circular form at the upper end, with a circular interior air-tube, *d*, in contact with the sides of said tube A, to form a steam-radiator tube, as shown and described.

ABNER A. GRIFFING.
